CRANKSHAFT LATHE

William F. Groene and Harold J. Sickmann,
 Cincinnati, Ohio, assignors to The R. K. Le
 Blond Machine Tool Company, Cincinnati,
 Ohio, a corporation of Delaware

Application February 21, 1938, Serial No. 191,718

13 Claims.

(CL. 82—9)

This invention pertains to crankshaft lathe and more particularly to lathes adapted to finish machining operations on the bearing portions of crankshafts. As an exemplary disclosure we show a machine adapted to simultaneously finish turn the line bearings, including the flange and stub ends, of a multiple throw internal combustion engine crankshaft. The lathe of this disclosure is one which is adapted to finish shave the line bearing and associated diameters and to finish trim the fillets adjacent said line bearings and flange and stub end portions of crankshafts which have been previously machined in such lathes as are illustrated in Patents Re. 19,905, dated March 31, 1936, Re. 20,090, dated September 1, 1936, and 2,069,107, dated January 26, 1937.

Heretofore, work which had been completed on lathes such as cited in the above three patents were ground in a rough grinding operation insofar as the line bearing diameters were concerned. In this rough grinding operation considerable time was required inasmuch as it is necessary in a grinding operation of this character to grind each of the line bearings separately in order to gain the proper degree of finish required. It is also found in rough grinding operations that it is extremely difficult to obtain the proper spacing between the fillets because of the break down of the grinding wheel side faces, with the result of the rapid deterioration of the wheel under frequent dressing necessary to maintain the sharp corners required for these fillets. Also during the rough grinding operation it is impractical to finish such portions as the stub end diameters and the flange and oil groove portions of the crankshaft. These portions were, therefore, not finished during the rough grinding operation and required further turning operations to complete them to their necessary high degree of turned finish.

It was also found that before the rough grinding operations could be undertaken it was necessary to re-straighten the crankshaft so that the excessive run-out would not damage the grinding wheel or require excessive amount of stock to be removed by grinding which, of course, is a much slower process than that of turning in removing the same amount of metal.

It is, therefore, the object of the present invention to eliminate the above objectionable features in order to finish machine the line bearings including the flange and stub ends of a crankshaft.

One object of our invention is to provide a lathe

which is adapted to simultaneously finish shave the line bearing diameters, to trim the fillet walls associated with said diameters and also to finish machine all of the stub end and flange end portions simultaneously in a single operation. 5

Another object of the invention is to provide a simplified feeding arrangement whereby a single tool bar moving in a single direction is capable of simultaneously accurately finishing the bearing diameter and also trimming the fillet 10 walls to a high degree of accuracy.

Still another object of our invention is to provide a novel tool holder containing a shaving tool for accurately machining the diameter of a crankshaft bearing a second series of cutting tools 15 adapted to face and neck the fillets associated with said bearings.

Other objects of this invention will be understood from the following detailed description of the drawings, in which:

Figure I is a front elevation of a crankshaft lathe incorporating the features of our invention shown adapted to simultaneously finish turn all of the line bearings, including the flange and stub end portions, of a crankshaft. 20

Figure II is a right hand end elevation of the lathe shown in Figure I.

Figure III is a vertical transverse section through the lathe shown substantially on the line III—III of Figure I.

Figure IV is an enlarged portion of the Figure III to more clearly show the relation of the cutting tools to the work piece. 30

Figure V is a horizontal section through the lathe on the line V—V of Figure IV. 35

The machine comprises a base 1 upon which are mounted tailstocks 2 and 3 having the usual centers 4 and 5 which may be axially reciprocated by the hand wheels 6 of the tailstocks. Also on the base 1 between the tailstocks 2 and 3 are the center drive chuck units 7 and 8 which carry the center drive ring gear chuck indicated generally at 9. Between the tailstock 2 and the center drive chuck housing 7 is mounted on the base 1 the flange end tool unit 10. Between the center driving chuck housings 7 and 8 is mounted on the base 1 the center line bearing tool unit 11, and between the center drive chuck unit 8 and the tailstock 3 is mounted the stub end tool unit 12. 40

Appropriate loading devices for inserting and removing the crankshaft from the center drive chucks 9 comprise the cranes 13 and 14 carried on the rail 15 which in turn is supported on standards 16 carried by the tailstocks 2 and 3 in 45 50 55

a manner fully disclosed in Patent 2,069,107, dated January 26, 1937.

The center drive ring gear chucks 9 are driven by the electric motor 17 mounted on the motor plate 18 which in turn is fixed on the base 1 of the lathe. The motor 17 has a driving pinion 19, (best seen in Figure II) which engages and drives the gear 20 fixed on the drive shaft 21 which is suitably journaled in the tool carrier units 10 and 12 and the center drive units 7 and 8. On the shaft 21, where it passes through the units 1 and 8, are fixed driving pinions 22 which in turn drive idler gears 23 carried on studs 24 fixed in the center drive chuck units 7 and 8, the idler gears 23 in turn driving the respective ring gears 25 of the center drive ring gear chuck 9 so that upon rotation of the driving motor 17 the center drive ring gear chuck 9 will be driven in synchronism to rotate the crankshaft C mounted therein.

The crankshaft C is gripped in the chucking devices 9 by means of a chucking mechanism for example of a character shown in Patent 2,030,020, dated February 4, 1936, and the ends of the crankshaft are supported on the centers 4 and 5 in the usual manner of a lathe.

In each of the tool carrier units 10, 11, and 12 is mounted a single tool bar 26 (best seen in Figure III) which is adapted to be moved to and from the axis of the work piece C in horizontal plane. The tool bar is reciprocated in this manner by means of a rock shaft 27 which is rotatably mounted in suitable bearings 28 carried in the rear of the tool carrier units 10, 11 and 12 and the center drive chuck units 7 and 8. On this rock shaft are fixed downwardly extending crank arms 29 which are connected to each of the tool bars 26 in the units 10, 11, and 12 by means of connecting rods 30 which are adjustably mounted at 31 in the wrist pins 32 of the downwardly projecting arms 29 for the purpose of adjusting the bar relative to the work piece for final sizing of the work diameter. The rock shaft 27 is actuated by means of the fluid pressure cylinder 33 which is pivotally mounted on a pin 34 carried in the upstanding boss 35 formed integral with the tool carrier unit 11 and having a piston rod 36 pivotally connected at 37 to a lever arm 38 connected to the rock shaft 27 so that reciprocation of the cylinder 33 and its piston rod 36 will cause rocking movement of the shaft 27 and thereby simultaneously feed all of the tool bars 26 in the tool carrier units 10, 11 and 12 to and from the work piece C in the lathe. Appropriate fluid pressure control means of conventional design for operating said cylinder 33 may be employed.

Noting in particular Figures IV and V it will be noted that on each of the tool bars 26 is mounted a novel tool holder 38 which contains shaving tools 40 for accurately finishing the diameters of the bearing portions 40a of the crankshaft and also contains facing tools 41 adapted to face the side walls 42 and to neck the fillets 43 to accurate finished dimensions. Appropriate back up screws 44 and 45 are provided for respectively adjusting and holding the tools 40 and 41 in correct cutting position.

The shaving tool 40 has its cutting edge 46 lying in a plane which is parallel with the plane of feeding of the tool bars 26 and tangent to the surface of the diameter 40a being machined but which has its cutting edge inclined at an angle to a plane passing through the axis of the work and normal to said first mentioned plane. The ob-

ject of this arrangement being that the entire cutting edge 46 is at no time operating on the diameter 40a being machined. With the full width of cutting edge 46 of the tool thus eliminated substantially all chatter and excessive strains on the work piece are eliminated which prevents marring the accurate finish required in this type machining operation. It will also be noted that the tools 41 for machining the fillets are so arranged in relation to the shaving tools 40, that both the tools 40 and 41 operate simultaneously upon the work piece and complete their machining operation simultaneously. These tools 41 have their cutting edges 47 so arranged that at the completion of the cutting cycle those edges 47 blend perfectly with the machined surface 40a produced by the cutting edge 46 of the shaving tool 40 resulting in a high degree of accuracy and finish for all of the vital surfaces 40a, 42 and 43 of the crankshaft bearings. It is also to be noted, referring to Figure I, that this same arrangement is employed for machining the flange end and the stub end portions in addition to all of the line bearing portions of the crankshaft C.

Having fully set forth and described our invention what we claim as new and desire to secure by U. S. Letters Patent is:

1. In a lathe, a rotatable work holder adapted to engage a work piece having cylindrical and radially extending surfaces, a tool carrier movable relative to said work piece perpendicular to its axis of rotation in the work holder, a tool holder carried on said tool carrier, a shaving tool mounted on said tool holder adapted to machine the cylindrical portion of said work piece, a facing tool mounted on said tool holder adapted to machine radially extending surface on said work piece, means for rotating said work holder, and means for feeding said tool carrier.

2. In a lathe, a rotatable work holder adapted to engage a work piece having cylindrical and radially extending surfaces, a tool slide movable perpendicular to the axis of rotation of said work piece, a cutting tool mounted on said tool slide having its cutting edge in a plane which is parallel to the movement of said tool slide and tangent to the cylindrical surface to be cut on said work piece and also having its cutting edge angularly related to a plane passing through the axis of rotation of said work piece in said work holder and normal to said first mentioned plane, facing tools mounted on said tool slide for machining said radially extending surfaces, means for rotating said work holder, and means for feeding said tool slide whereby all of said tools simultaneously perform their machining operations.

3. In a crankshaft lathe, means for supporting and rotating a crankshaft having a bearing comprising a cylindrical diameter and associated radially extending fillets, a tool slide movable relative to said bearing, a shaving tool mounted on said tool slide for machining said cylindrical diameter portion, facing tools also mounted on said tool slide for machining said fillets, said tools being arranged to simultaneously perform their machining operations on the respective portions of said bearing, means for rotating said work holder, and means for feeding said tool slide.

4. In a crankshaft lathe, a base, a pair of tailstocks mounted on said base, axially movable centers in said tailstock adapted to engage the ends of a crankshaft, center drive chucking devices mounted on said base between said tailstocks, tool feeding devices mounted on said base

- between and each side of said center drive chucking devices, a tool bar mounted in each of said tool feeding devices, cutting tools mounted on said tool bars for engaging bearing portions of said crankshaft, a feed crankshaft mounted on said center drive chucking devices and tool feeding devices, connecting means between said tool bars and said feed crankshaft, a single hydraulic feed cylinder pivotally mounted on one of said tool feeding devices and connected to said feed crankshaft for rocking same, fluid pressure means for actuating said hydraulic cylinder whereby all of said tool bars may be simultaneously fed relative to said crankshaft in said lathe, and means for rotating said center drive chucking devices.
5. In a crankshaft lathe, a base, tailstocks mounted on said base, axially movable centers in said tailstocks adapted to engage the ends of a crankshaft in said lathe, center drive chucking devices mounted on said base between said tailstocks, tool carrier units located between said center drive chucks and each side thereof and mounted on said base, a tool bar in each of said tool carrier units, cutting tools on said tool bars adapted to engage bearing portions of said crankshaft, a feed crankshaft mounted on said tool carrier unit, connecting means between the throws of said crankshaft and each of said tool bars, a single hydraulic feed cylinder pivotally mounted on a tool carrier unit between said center drive chucking devices, means for connecting said cylinder to said feed crankshaft, fluid pressure means for actuating said cylinder whereby said feed crankshaft may be rocked for simultaneously feeding all of said tool bars, and means for rotating said center drive chucking devices.
6. In a crankshaft lathe, means for supporting and rotating a crankshaft so as to expose all of its line bearings including its flange and stub ends for machining operations, tool feeding devices movable relative to said crankshaft, shaving tools carried by said tool feeding devices for machining all of the cylindrical portions associated with said line bearings, flange, and stub ends, facing tools carried by said tool feeding devices for machining all of the radially extending surfaces associated with said cylindrical portions, and means for actuating said tool feeding devices to cause all of said tools to simultaneously perform their respective machining operations, and means for rotating said supporting and rotating means.
7. In a crankshaft lathe, means for supporting and rotating a crankshaft intermediate its ends, tool feeding devices adapted to be fed relative to all of the line bearings, flange, and stub ends of said crankshaft, shaving tools carried by said tool feeding devices for machining the diameters of the line bearings and also the diameters of the stub end and flange end portions of said crankshaft, further tools also carried by said tool feeding devices adapted to face and neck the fillets associated with said line bearing diameters and to neck and face the radially extending surfaces associated with the stub and flange end of the said crankshaft, means for rotating said supporting and rotating means, and means for simultaneously actuating all of said tool feeding devices.
8. In a lathe, a rotatable work holder adapted to engage a work piece having cylindrical and radially extending faces, a tool slideable to and from the axis of rotation of said work piece in the work holder, a cutting tool mounted on said tool slide adapted to tangentially engage said cylindrical work surface to be machined, a second cutting tool mounted on said tool slide adapted to engage said cylindrical surface perpendicular to a plane tangent to the work surface at the point of engagement of said second mentioned tool, means for rotating said work holder and means for feeding said tool slide to cause said tools to simultaneously act upon said work piece.
9. In a lathe, a rotatable work holder adapted to engage a work piece having a cylindrical surface and a radially extending surface associated therewith, a tool slide associated with said work holder and adapted to feed perpendicular to the axis of rotation of said work piece in said work holder, a cutting tool mounted on said tool slide adapted to engage said cylindrical surface tangentially, a second cutting tool adapted to machine said radially extending surface and having a cutting edge adapted to engage said cylindrical surface from a direction perpendicular to a plane tangent to said cylindrical surface at the point of contact of said second mentioned tool, means for rotating said work holder, and means for feeding said tool slide.
10. In a lathe, a rotatable work holder adapted to engage a work piece having a cylindrical portion and a radially extending surface associated with said cylindrical surface, a tool slide movable relative to the axis of rotation of said work piece in said work holder, a shaving tool adapted to be fed tangentially past the cylindrical surface being machined, a facing tool mounted on said tool slide adapted to be fed perpendicular to said axis of rotation of said work piece for machining said radially extending surface of said work piece, means for rotating said work holder, and means for actuating said tool slide to cause said cutting tools to simultaneously operate upon said work piece.
11. In a lathe, a rotatable work holder adapted to engage a work piece having cylindrical and radially extending surfaces, a shaving tool having its cutting edge lying in a plane which is parallel with the plane of relative feeding of the tool and work piece and having its cutting edge inclined at an angle to a plane passing through the axis of work rotation in the work holder and normal to said first mentioned plane, a facing tool associated with said shaving tool adapted to be fed simultaneously with said shaving tools to machine the radially extending surfaces of said work piece, means for rotating said work holder, and means for effecting feeding movements in said tool.
12. In a lathe, a tool holder adapted to be fed relative to the axis of rotation of a work piece in a work holder in said lathe, means on said tool holder for supporting a cutting tool with its cutting edge lying in a plane which is parallel with the plane of relative feeding of said tool holder and work piece and tangent to the surface of a diameter to be machined on said work piece and having its cutting edge inclined at an angle to a plane passing through the axis of work rotation and normal to said first mentioned plane, means on said tool holder for supporting a cutting tool having its cutting edge arranged to machine a radially extending surface on said work piece and having its cutting edge so arranged as to blend perfectly with the surface machined by said first mentioned tool at the completion of the cutting cycle, means for rotating said work holder, and means for feeding said tool holder to effect simultaneous operation of said cutting tools on said tool holder.

13. In a crankshaft lathe, means for supporting and rotating a crankshaft, a tool bar movable to and from the axis of rotation of a work piece in said means, a shaving tool fixed on said bar for machining a bearing diameter on said crankshaft, facing tools fixed on said bar for machining the fillets associated with said bearing diameter, means for actuating said supporting

and rotating means, and means for feeding said tool bar relative to said work piece in said work holder for simultaneously accurately finishing the bearing diameter and associated fillets of said crankshaft.

CERTIFICATE OF CORRECTION.

Patent No. 2,191,347.

February 20, 1940.

WILLIAM F. GROENE, ET AL.

It is hereby certified that error appears in the printed specification of the above numbered patent requiring correction as follows: Page 3, first column, line 72, claim 8, for the words "tool slidable" read tool slide movable; and second column, line 12, claim 9, for "theerwith" read therewith; and that the said Letters Patent should be read with this correction therein that the same may conform to the record of the case in the Patent Office.

Signed and sealed this 16th day of April, A. D. 1940.

(Seal)

Leslie Frazer
Acting Commissioner of Patents.
